BENJAMIN McINNERNEY, OF COUNCIL BLUFFS, IOWA.

TRIPPING DEVICE.

1,408,108.

Specification of Letters Patent. Patented Feb. 28, 1922.

Application filed January 16, 1919. Serial No. 271,483.

To all whom it may concern:

Be it known that I, BENJAMIN McINNERNEY, a citizen of the United States, and a resident of Council Bluffs, in the county of 5 Pottawattamie and State of Iowa, have invented a new and useful Improvement in Tripping Devices, of which the following is a specification.

My invention relates to tripping devices 10 for circuit interrupters and particularly to tripping devices that are responsive to overload, phase reversal and phase failure.

One object of my invention is to provide a 15 tripping device, of the above-indicated character, having a single-supporting member that shall constitute a portion of the magnetic circuit of the device.

Another object of my invention is to provide a phase-responsive relay for a device 20 of the above-indicated character that shall be applicable to either two or three-phase circuits.

A further object of my invention is to provide a tripping device of the above-indicated 25 character that shall be simple and inexpensive to construct and effective in its operation.

In practicing my invention, I provide a magnetizable member of substantially S- 30 shape that is secured to the supporting panel of the circuit interrupter. A coil is disposed between two of the arms of the magnetizable member and, together with its movable core member, constitutes an overload relay. A 35 phase-responsive relay, having two coils that may be connected to either two or three-phase circuits, is supported on the magnetizable member and is provided with an armature that is adapted to be maintained in its 40 upper position so long as the correct phase relation obtains in the circuit. A movable tripping rod is supported on a projection on the movable core member of the overload relay and is adapted to be actuated by the 45 overload relay and by the phase-responsive relay. A device of this character is relatively inexpensive to construct because of the simplicity and the double function of its component parts.

Figure 1 of the accompanying drawings is 50 a side elevational view of a circuit interrupter embodying my invention; Fig. 2 is a front elevational view of the interrupter shown in Fig. 1; Fig. 3 is a diagrammatic view of a phase-responsive relay illustrating the connections of the same for two- 55 phase operation, and Fig. 4 is a diagrammatic view of a phase-responsive relay illustrating the connections of the same for three-phase operation.

A circuit interrupter 1 comprises, in general, a supporting panel 2, main stationary contact members 3, auxiliary stationary contact members 3^a, a movable bridging contact member 4 that is mounted on a pivotally-supported arm 5 upon which auxiliary contact members 4^a are also mounted, an actuating device 6 and a tripping device 7.

The arm 5 is pivotally mounted on brackets 8, and an operating handle 9, that is also mounted on the brackets 8, is adapted to actuate the arm 5 in a well known manner to effect engagement of the contact members. The operating device 6 is provided with a projection 11 on the handle 9 that is engaged by a latch 12 for the purpose of holding the contact members in engagement. A manually actuated member 13 is provided for actuating the latch 12, and a bell-crank lever 14 is mounted on the panel 2 and so connected to the latch 12 as to cause the same to be actuated by the tripping device 7.

The tripping device 7 comprises a magnetizable member 20 of substantially S-shape, an overload relay 21 and a phase-responsive relay 22. A coil 23 is disposed between two arms 24 and 25 of the magnetizable member 20 which constitutes the stationary magnetizable member of the overload relay 21. A movable core member 26 is disposed within the coil 23 and is provided with a projection 27 for normally supporting a tripping rod 16. The movable member of a dash pot 28 is operatively connected to the lower end of the movable core member 26, and the stationary member 29 of the dash pot is mounted on the arm 30 of the member 20. A magnetizable core member 31 is mounted on a projection 32 on the arm 30 and is provided with five polar projections 33. A keeper member 34 is also mounted on the projection 32, and a segmental armature 35 is disposed in the air gap between the keeper member and the core member 31. The armature 35 is pivotally mounted on a bracket 36 and has a projection 37 that is adapted to engage the tripping rod 16, under predetermined conditions. The armature 35 is of such weight that it normally remains in its lowermost position 110 when no current traverses the windings 38 and 39 of the relay.

The windings 38 and 39 of the phase-responsive relay are so disposed about the three inner polar projections of the core member 31 that a shifting magnetic field is set up which induces such eddy currents in the armature 35 as to maintain the same in its upper position, under correct phase relation in the circuit to which the same is connected.

10 When an overload obtains on the circuit that is connected to the circuit interrupter 1, the movable core member 26 of the overload relay 21 will be moved upwardly to thereby cause the rod 16 to engage the projection 15 on the bell-crank lever 14 and thus so actuate the latch 12 as to permit the disengagement of the contact members. The time of operation of the rod 16 may be controlled by the dash pot 28 and, consequently, may be inversely responsive to the overload. The stationary member 29 of the dash pot guides the movable core member 26 and thus serves the double purpose of controlling the time of operation and for guiding the same.

When the phase relation in the circuit to which the phase-responsive relay is connected is changed, the weight of the armature 25 will overcome the electrical 30 pulsion and cause the same to move downwardly and thus the projection 37 will actuate the tripping rod 16, substantially as heretofore set forth. Similarly, when no current traverses one of the phases of the 35 circuit to which the relay 22 is connected, the armature 35 will move downwardly and thus trip the interrupter 1.

Since the single supporting member 20 of the overload and phase-responsive relays 40 constitutes a part of the magnetic circuit of the overload relay, the device may be inexpensive to construct and, since the phase-responsive relay is applicable, without changing the windings of the same, in eith-

er two or three-phase circuits, the device is 45 adaptable for a relatively wide range of application and is efficient in its operation.

I do not limit my invention to the particular structures illustrated, as it may be variously modified without departing from 50 the spirit and scope of the invention, as set forth in the appending claims.

I claim as my invention:

1. A tripping device for a circuit interrupter comprising a magnetizable member 55 of substantially S-shape, a coil disposed between two arms of the magnetizable member that constitute a magnetic circuit therefor, a movable core member for the coil, a reciprocable rod actuated by the movable core member, and a reverse-phase relay mounted on the other arm of the magnetizable member and having means for actuating the reciprocable rod.

2. The combination with a supporting 65 panel, of a magnetizable member of substantially S-shape secured to the panel, a coil disposed between two arms of the magnetizable member that constitute a magnetic circuit therefor, a movable core member for 70 the coil, an actuating rod normally resting on a projection on the movable core member, and a reverse-phase relay mounted on another arm of the magnetizable member and adapted to actuate the actuating rod. 75

3. The combination with a coil and a reverse-phase relay, of a single supporting member for the coil and the relay, said supporting member constituting the stationary magnetizable member for the coil, 80 an actuating rod, a movable core member for the coil, and means whereby the rod may be actuated by the relay and the movable core member of the coil.

In testimony whereof, I have hereunto 85 subscribed my name this 7th day of December, 1918.

BENJAMIN McINNERNEY.
